US0D1068745S

(12) **United States Design Patent** (10) Patent No.: **US D1,068,745 S**
(45) Date of Patent: ** Apr. 1, 2025

(54) **TRIPOD FOR HOLDING MUSIC
ACCESSORIES**

(71) Applicant: **MUSIC EXPRESS LLC**, Kingston, WA (US)

(72) Inventors: **Ryan Kallas**, Kingston, WA (US); **J. Herschel Blankenship**, Kingston, WA (US)

(73) Assignee: **MUSIC EXPRESS LLC**, Kingston, WA (US)

(**) Term: **15 Years**

(21) Appl. No.: **29/918,820**

(22) Filed: **Nov. 30, 2023**

Related U.S. Application Data

(63) Continuation of application No. 29/740,945, filed on Jul. 8, 2020, now Pat. No. Des. 1,015,311, which is a continuation of application No. 29/623,444, filed on Oct. 25, 2017, now Pat. No. Des. 890,142, which is a continuation of application No. 29/502,138, filed on Sep. 12, 2014, now Pat. No. Des. 801,315, which is a continuation of application No. 29/421,803, filed on Sep. 26, 2012, now Pat. No. Des. 714,267.

(57) **CLAIM**

The ornamental design for a tripod for holding music accessories as shown and described.

DESCRIPTION

FIG. 1 is a front perspective view of a tripod for holding music accessories showing the new design;

FIG. 2 is a side perspective view thereof;

FIG. 3 is an enlarged partial perspective view thereof;

FIG. 4 is a top perspective view thereof;

FIG. 5 is an enlarged partial perspective view thereof; and, FIG. 6 is a bottom perspective view thereof.

The broken lines depict portions of the tripod for holding music accessories that form no part of the claimed design.
